(57) **CLAIM**

The ornamental design for a brooch watch, as shown and described.

DESCRIPTION

FIG. 1 is a perspective view of the design of a brooch watch; FIG. 2 is a front view of the design of a brooch watch; FIG. 3 is a back view of the design of a brooch watch; FIG. 4 is a first side view of the design of a brooch watch; FIG. 5 is the other side view of the design of a brooch watch; FIG. 6 is a top view of the design of a brooch watch; and, FIG. 7 is a bottom view of the design of a brooch watch. The broken line showings of dial and closure structures are for illustrative purposes only and form no part of the claimed design.
